UNITED STATES PATENT OFFICE

2,555,086

COLOSTOMY PROTECTOR

J. Edwin Quinn, Ithaca, N. Y., assignor to Etna Appliance and Equipment Co., Inc., Dryden, N. Y., a corporation of New York

Application June 7, 1950; Serial No. 166,598

2 Claims. (Cl. 128—283)

1

This device is particularly useful to those who have undergone the operation known as a colostomy, by which the normal outlet of the lower intestine is changed to an opening in the abdominal wall made by an incision in the side. Since the person has little control over the discharges, it is necessary that some sort of a receptacle be worn, if the person is to lead any sort of a normally active life. The colostomy sacks previously used have not been entirely satisfactory for a number of reasons. They have usually involved a rubber sack, or at least a rubber washer against the skin around the colostomy opening. Rubber and other soft materials have a tendency to absorb odors which cannot be entirely removed by ordinary washing; and any broad soft washer element tends to cause perspiration and chafing. In any article continuously worn on the body it is important that the skin be maintained in as normally dry condition as possible. Another source of odor has been the gases over which the patient has no voluntary control. It has also been found that loose bags or sacks tended to become bulky, were hard to clean, and because of the looseness precluded the person from taking part in various beneficial sports such as swimming, long walks or dancing.

The objects of the present invention are to provide a colostomy protector which can be comfortably worn without attracting attention; that will be lighter and more durable than previous devices; that can be easily cleaned and will not absorb odors; that will eliminate all rubber or other soft materials in the receptacle or against the skin; provide for the neutralization of gaseous odors; and to permit light to pass thru the device for its beneficial action on the skin.

Other objects are to encourage more normal physical activities to benefit the general health; to reduce the cost of manufacture; and to reduce the cost to the patient. Unlike some of the more elaborate devices now on the market, the present device, with reasonable care, will last a long time.

Referring now to the drawings,

Fig. 1 is a front view of the device.

Fig. 2 is an elevation of Fig. 1, as seen from the lower side.

Fig. 3 is a transverse cross-sectional view showing in greater detail the odor neutralizing apparatus, the body pressure plate and seals.

Fig. 4 is a cross-sectional view on the line 4—4 of Fig. 3 showing the separator plate in the odor neutralizing device.

2

Fig. 5 illustrates the general manner of wearing the colostomy protector and belt.

Similar reference numerals refer to similar parts thruout the various views.

5 Referring now to Fig. 1, the colostomy protector consists of a receptacle or chamber 1 having a generally rectangular shape as viewed from the front and provided with sloping walls 2 inclining inward toward the top or outward toward the body, this tapered form being best illustrated in Fig. 2 and Fig. 3.

10 In Fig. 3 the human body 3 is shown having the colostomy opening 4 thru which digested material flows into the chamber 1. The colostomy protector is held in place on the person's body by a strap or belt 5 as shown in Fig. 5, the belt 5 preferably ending in pairs of attaching tapes 6 having fasteners 7 as shown in Fig. 1 and Fig. 2. These tapes 6 pass thru the slots 8 in the outer flange or rim 9 of the protector.

15 While the chamber 1 is approximately rectangular as viewed in Fig. 1, its rim where it touches the body is not of strictly straight lines, but is curved on arcs to fit the normal contours of the body as shown in Fig. 2 and Fig. 3. Though the general configuration of the protector is accordingly convex, its outer flange 9 is curled back as shown best at the right and left of Fig. 3, the curl going all the way around the protector as indicated in dotted line, the outer edge of the flange 9 terminating in a smoothly rounded bead 9'. This upward or outward curve of the rim 9 and its smoothly rounded edge 9' permit the person to bend freely and take any normal posture without danger of chafing or cutting the skin. The slots 8 are located near the edge 9' and far enough up on the curled back rim 9 so that the tapes 6 are not pressed into the person's body by the underside of the rim 9.

20 At the inner side of the flange 9 and under the base of the sloping wall 2 there is provided a rounded groove 10 which has no sharp edges to cut the skin but creates a natural seal by reason of the skin projecting into the groove 10 when in use. On the innermost side of this sealing groove 10 a rounded wall 11 provides the primary or first seal which the effuvia in the colostomy protector meets. An effuvia which works past that point encounters the rounded groove 10 as the second seal; and finally the broad flange 9 which is close against the skin for a considerable distance constitutes the tertiary or outer seal.

25 It is important that these seals, and indeed any portion of the apparatus that may come into

contact with the effuvia, should not involve the use of rubber or other soft material which might have a tendency to absorb odors. It has been found that odors penetrate rubber and often cannot be eradicated by washing.

In any such apparatus that must be continuously worn there is always the danger of harming the skin. Therefore not only should the device be hard and impervious to moisture and acids, and without sharp corners or edges, but also it should in all ways provide as natural conditions as possible. This colostomy protector is therefore made of translucent or transparent plastic material. This permits some light to reach the skin from time to time as on other portions of the body that are usually covered, with a generally beneficial effect. In addition this provides a window or translucent panel thru which the wearer may observe the conditions within the receptacle. Furthermore, when light can pass thru the device, it is more likely to be thoroughly washed and cleaned.

In addition to the digested material discharging from the colostomy, there is also considerable gas. Since the patient has no voluntary control of this gas, its odor may become embarrassing. If not allowed to escape it may create dangerous pressures. There is therefore provided a deodorizing filter 15 covered by a removable cap 16 having orifices 17 thru which gas can escape. This cap 16 is screwed on the rim 18 of the main opening 19 in the top of the chamber 1. A perforated disk 20, best seen in Fig. 4, may be used to support the filter pad 15. Where the filter 15 is of sufficiently rigid material the separator 20 may be omitted. Numerous deodorizing materials permeable to gas are well known in the art, and this construction permits the use of almost any of them as desired. The filter material can be readily changed by unscrewing the cap 16, and there is nothing in the rest of the device to hold or absorb odors.

The particularly advantages of this form of colostomy protector are as follows: the device is sufficiently rigid and compact so that it does not attract attention with ordinary clothes or even with a bathing suit, and it can be comfortably worn; being principally of one piece it is simple to manufacture, and less expensive than the sack types. It is light and durable, with no parts to replace except the deodorizing material. The device is much easier to keep clean than more complicated types, and there is no rubber to absorb odor. Finally, its transparency makes it possible for the user to take better care of himself and the apparatus, warning him when it is getting too full, assisting him to clean it, and permitting the light to reach the skin.

While I have in the foregoing described a certain specific form of the device by way of example, it will be understood that it is merely for purposes of illustration to make clear the principles of the invention, which is not limited to the par-

ticular form shown but is susceptible to various modifications and adaptations in different installations as will be apparent to those skilled in the art without departing from the scope of the invention as stated in the following claims.

I claim:

1. In a colostomy protector, the combination of a chamber having tapering walls and a translucent top, said top having an orifice, a cap on said orifice, said cap having ventilating holes, a deodorant for neutralizing gases passing thru said cap, the base of said tapering walls having an inner rounded edge extending around the chamber to act as a primary seal against the escape of effuvia from within the chamber, a secondary seal consisting of a rounded groove immediately back of the primary seal and extending around the chamber, a tertiary seal consisting of a rim flange extending around the chamber and adapted to contact the body near the chamber, said rim having an outer portion of the flange curved away from the body, said outer portion having a smoothly rounded edge, slots in said flange near said edge to hold a supporting belt, the primary, secondary and tertiary sealing portions as they extend around the chamber being curved to approximate the contours of the body where they press upon it so as to avoid concentration of pressure on the patient's skin.
2. In a colostomy protector, the combination of a chamber having tapering walls and a top, said top having an orifice, a cap on said orifice, said cap having ventilating holes, a deodorant for neutralizing gases passing thru said cap, the base of said tapering walls having an inner rounded edge extending around the chamber to act as a primary seal against the escape of effuvia from within the chamber, a secondary seal consisting of a rounded groove immediately back of the primary seal and extending around the chamber, a tertiary seal consisting of a rim flange extending around the chamber and adapted to contact the body near the chamber, said rim having an outer portion of the flange curved away from the body, said outer portion having a smoothly rounded edge, slots in said flange near said edge to hold a supporting belt, the primary, secondary and tertiary sealing portions as they extend around the chamber being curved to approximate the contours of the body where they press upon it so as to avoid concentration of pressure on the patient's skin.
